Armais Arutunoff, Bartlesville, Okla., assignor to Reda Pump Company, Bartlesville, Okla., a corporation of Delaware

Application October 7, 1954, Serial No. 460,934

10

9 Claims. (Cl. 263—15)

This invention relates to melting furnaces of the direct fired, stack loaded type generally similar to those disclosed in my former Patents Nos. 2,674,446 and 2,680,609. More particularly, the invention consists in new and useful improvements in air pre-heaters for use in connection with furnaces of the type above referred to.

Various means have been employed for preheating the air fed to furnace blowers, but generally speaking, these pre-heaters have formed an integral part of the furnace structure and relied upon a heat exchange with the products of combustion discharged from the furnace.

The primary object of the present invention is to provide a pre-heater, in the form of a substantially rectangular housing adapted to be placed over the lid of the furnace and connected by its own integral duct, to the blower intake, inlet means being provided on the under side of the housing to receive the highly heated air radiating from the lid, whereby pre-heated air is drawn into the blower at the burner end of the furnace.

Another object of the invention is to provide a pre-heater for direct fired melting furnaces, consisting of a very simple sheet metal structure which may be applied to the furnace without altering the structure of the latter.

A further object of the invention is to provide a pre-heater of the type referred to which will materially lower the melting time of the furnace, reduce the fuel consumption, and minimize element loss or burn-outs.

Still another object of the invention is to provide a pre-heater which may easily be applied to and removed from the furnace for purposes of repair and cleaning.

A still further object of the invention is to provide a pre-heater which simply rests upon the furnace lid and is so connected to the blower intake as to permit a hinge action to allow the tilting of the pre-heater from the furnace lid to facilitate access to the furnace.

With the above and other objects in view which will appear as the description proceeds, the invention consists in the novel features herein set forth, illustrated in the accompanying drawings and more particularly pointed out in the appended claims.

Referring to the drawings in which numerals of like character designate similar parts throughout the several views,

Figure 1 is a view in side elevation, showing my improved pre-heater in place on the lid of a furnace.

Figure 2 is an end view showing the attachment of the pre-heater duct, to the blower air intake.

Figure 3 is a top plan view of the pre-heater.

Figure 4 is an enlarged sectional detail, taken on line 4—4 of Figure 3, showing the mounting bracket, and

Figure 5 is a sectional view taken on line 5—5 of Figure 3.

In the drawings, referring to Figures 1 and 2, 6 generally represents the body portion of a stack-loaded, direct-fired melting furnace of the oscillatory type such as described in my said former patents. The main shell of the furnace body is formed of vertical sheet metal side

2

walls 7 and end walls 8, all welded or otherwise jointed together and to the bottom (not shown) to form a box-like container. The top edges of the vertical walls 7 and 8 are provided with outwardly directed flanges or angle irons 9 which preferably extend entirely around the top of the furnace shell to accommodate complementary flanges 10 on the furnace stack 11 which overlies one end of the furnace body, and serving also to attach the main furnace closure or lid generally indicated by the numeral 12.

As explained in my said former patents, the furnace shell is lined with refractory brick arranged to provide a trough-like receptacle or accumulator, one end of which communicates with the overlying stack shell 11 which is likewise lined with refractory brick within its three fixed walls. The refractory lining of the furnace proper may extend slightly above the upper extremities of the shell walls 7—8 as shown at 13, to directly support the overall lid structure 12. The lid 12 consists of horizontal slabs 14 of refractory material arranged to bridge the top opening of the furnace proper, their opposite extremities being embraced by transversely extending channel members 15, preferably arranged in pairs overlying each of the lid slabs 14. The opposite ends of each of the cross channels 15 is bent downwardly and outwardly as at 16 to overlie the flanges 9 on the upper edges of the furnace shell walls. When in place, the ends 16 of the cross channels are normally vertically spaced from the flanges 9 so as to allow for tightening when bolts 17 are inserted in registering openings in the ends 16 and flanges 9 respectively.

As is the case of my said former patents, the stack 11 has three lined shell walls which border that end of the furnace, the stack being closed on the furnace side by removable closure slabs 18 of refractory material. These are held in place by channels 19 similar to channels 15 and provided with securing bolts 20 at each end, engaging vertical flanges 21 on the edges of the side walls 11 of the stack.

At the opposite end, the furnace is provided with a burner blower assembly 22, mounted on the furnace end wall by a bracket 23 and having an air fuel mixture discharge conduit 24 leading to the interior of the furnace and terminating in a burner nozzle (not shown). The blower 25 is provided with the usual air intake housing 25, generally frusto-conical in shape and provided at its flaring inlet end with a rotatable damper (not shown) having a radially projecting control arm 27.

A fuel supply line 28 is connected to the burner blower assembly by a feed extension 29 leading to the axis of the blower 22 and the furnace body may be mounted for oscillation by any conventional means, the mounting 26 shown in the drawings, being generally similar to those described in my said former patents.

The description thus far has been directed to the furnace structure so as to clarify the environment for which my pre-heater was primarily designed. It will be understood however, that the basic principle of the present invention may be employed with furnaces of different specific constructions which lend themselves to this type of pre-heating.

Turning now to the pre-heater itself, it will be seen from Figures 1 to 3 that it comprises a substantially rectangular box-like housing 30 preferably formed of sheet metal. The housing has a top wall 31 and side walls 32 and 33 and is of sufficient transverse and longitudinal dimensions to substantially overlie the furnace lid 12 as will hereinafter appear. The bottom wall 34 of the housing 30 is provided with an enlarged rectangular opening 35 shown in dotted lines in Figure 3 and of sufficient size to expose the major portion of the interior of the housing to the heat radiated from the furnace lid

12. The end of the housing adjacent the stack 11 is open and spaced laterally from the lid closure 18 to permit manipulation of the lid slabs. However, the bounding edges of said opening may be bent inwardly to form reinforcing flanges 36 as shown in Figure 1.

The opposite end wall 37 of the housing is preferably angularly disposed and terminates at one side of the housing in an integral duct 38 formed by the combined extensions of the top, bottom and side walls of the housing. This duct is turned downwardly at its end which carries a horizontally disposed, cylindrical extension 39, by means of which the duct is connected to the air inlet opening of the blower 22. Preferably, the cylindrical extension 39 is formed with upper and lower sections flanged as at 40 and secured together by bolts or the like 41.

The diameter of the cylindrical extension 39 permits it to fit over and tightly embrace the flaring air inlet housing 25 of the blower 22 when the bolts 41 are secured and the periphery of its upper section is provided with a transverse slot 42 to accommodate the damper control arm 27. The fuel feed extension 29 is accommodated by a suitable opening 43 in the end wall of the cylindrical extension 39 and passes axially through the latter for connection to the burner element of blower 22.

The entire housing 30 normally rests upon top edges of the channels 15 of the lid 12 and is pivotally supported by its duct and cylindrical extension 39 which fits around the blower intake housing. However, as an added measure of support, the cylindrical extension 39 is preferably provided with a transverse bracket member 44 which may be welded to the inner walls of the extension 39 and is provided centrally with an arcuate recess 45 adapted to fit over the fuel feed extension 29 as shown in detail in Figure 4. A substantially U-shaped yoke 46 underlies the feed extension 29 and is secured to the bracket 44 by means of screws or bolts 47. This bracket arrangement, together with the pivotal relationship of the cylindrical extension 39 on the blower intake housing 25, permits the pre-heater housing 30 to be bodily tilted in counter-clockwise direction from the position shown in Figure 1. Further pivotal support can be afforded by engagement of the outer end of feed extension 29, by the concentric opening 43 in the side wall of the duct 38 which closes the end of the cylinder 39. In other words, a three-point pivotal support is provided by the air inlet housing 25, the bracket 44 and the opening 43.

In order to add rigidity to the housing 30, I preferably provide a series of longitudinally extending, laterally-spaced angle irons 48 which may be welded to the under side of the top wall 31. Also if desired, one transverse angle iron 49 may be provided adjacent the inlet end of the housing to prevent sagging of the top wall.

In operation, the housing 30 receives its air supply through the bottom opening 35 and the end opening 36, the air having been pre-heated by the radiated temperature from the furnace closure slabs 14 and the stack closure slabs 18 which heat would otherwise have been wasted and dissipated in the surrounding atmosphere. The bottom wall 34 of the housing, being supported on the top horizontal edges of the cross channels 15, is thereby spaced vertically from the top surfaces of the slabs 14. Thus, hot air may enter the bottom opening 35 of the housing all along the lid and between the flanges of the channels 15. The pre-heater raises the temperature of the air at the blower intake 25 to approximately 200° F. which of course, reduces the amount of oxygen in a given volume of air pumped into the furnace. However, blowers of the type employed with these furnaces are of sufficient capacity to more than compensate for this reduction in oxygen. Experiments have shown that melting time on gray iron (i. e. from charged to pour) is reduced by approximately 10 percent, or, conversely, the metal temperature will be higher for the same length of time. Fuel consumption is actually reduced by more than this

amount, due to less time as well as less air and consequently less fuel going into the furnace. Losses of elements (carbon and silicon) are greatly reduced, due to less time exposed and, because the heated air tends to mix better with the fuel, gives not only better combustion but less free oxygen over the bath.

The same benefits would obviously be derived in connection with brass and bronze melting. In fact, even greater benefits might be expected from the standpoint 10 of oxidation of white metals from red brasses. Obviously any reduction in melting rates is always advantageous as is the lowering of fuel costs.

It has been my experience that approximate reduction 15 in melting time have been on the order of 15 percent; fuel savings on the order of 20 percent; and carbon and silicon losses have been reduced to nil on ordinary gray iron alloys. On exceptionally high carbon metals, such as used for ductile iron, carbon losses are reduced to a limit that causes no concern in production. In fact, by use of 20 an admixture of oil with gas fuel, carbon can be maintained at any desired level. In lower carbon irons (below about 3.10C) the level can actually be increased.

From the foregoing it is believed that my invention may be readily understood by those skilled in the art without 25 further description, it being borne in mind that numerous changes may be made in the details disclosed without departing from the spirit of the invention as set forth in the following claims.

I claim:

30. 1. In a melting furnace having a melting chamber, a burner-blower assembly at one end and a removable lid bridging the top of said chamber; an air pre-heater for said burner-blower, comprising a substantially box-like housing overlying said lid with its underside in vertically spaced relation and supported thereby, air inlet means on the underside of said housing directly exposed to the top surface of said lid, a duct at one end of said housing, and means connecting said duct to the air inlet of said burner-blower assembly.
40. 2. In a melting furnace having a melting chamber, a vertical loading stack at one end of said chamber, a burner-blower assembly at the other end of said chamber, a removable lid bridging the top of said chamber, and a removable closure for the vertical wall of said stack facing said chamber; an air pre-heater for said burner-blower, comprising a relatively shallow box-like housing overlying said lid with its underside in vertically spaced relation and supported thereby, openings on the underside and the end of said housing adjacent said stack, to receive heated air drawn across the hot surfaces of said lid and stack closure, the other end of said housing terminating in a duct, and means connecting said duct to the air inlet of said burner-blower assembly.
45. 3. In a melting furnace having a melting chamber, a burner-blower assembly at one end and a removable lid bridging the top of said chamber; an air pre-heater for said burner-blower, comprising a substantially box-like housing of sheet metal, overlying said lid with its underside in vertically spaced relation and supported thereby, air inlet means on the underside of said housing directly exposed to the top surface of said lid, one end of said housing terminating in a duct, and means connecting said duct to the air inlet of said burner-blower assembly.
50. 4. A device as claimed in claim 3, wherein said housing is pivotally mounted with respect to said lid.
55. 5. In a melting furnace having a melting chamber, a vertical loading stack at one end of said chamber, a burner-blower assembly at the other end of said chamber, a removable lid bridging the top of said chamber and a removable closure for the vertical wall of said stack facing said chamber; an air pre-heater for said burner-blower, comprising a relatively shallow box-like housing of sheet metal, overlying said lid with its underside in vertically spaced relation and supported thereby, openings 60 on the underside and the end of said housing adjacent

said stack, to receive heated air drawn across the hot surfaces of said lid and closure, the other end of said housing terminating in a duct, and means connecting said duct to the inlet of said burner-blower assembly.

6. Apparatus as claimed in claim 5, wherein said housing is pivotally mounted with respect to said lid.

7. Apparatus as claimed in claim 5, wherein said duct is connected to said burner-blower assembly by a cylindrical extension coaxial with the latter, and means supporting said extension for rotary movement about the axis of said burner-blower.

8. In a melting furnace having a melting chamber, a burner-blower assembly including an air inlet flange, at one end of said chamber, a horizontal fuel conduit leading to the burner coaxially of said inlet flange, and a removable lid bridging the top of said chamber; an air pre-heater for said burner-blower, comprising a substantially box-like housing overlying said lid with its underside in vertically spaced relation and supported thereby, air inlet means on the underside of said housing directly ex-

posed to the top surface of said lid, a downwardly directed duct at one end of said housing overhanging the burner-blower end of said chamber, a substantially cylindrical extension at the lower extremity of said duct, projecting horizontally therefrom with its free end embracing said air inlet flange, and means supporting said extension and housing for rotation about the horizontal axis of said flange.

9. Apparatus as claimed in claim 8, wherein said extension rotatably embraces the periphery of said flange.
